UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

SHADE-HOLDER.

1,245,177.

Specification of Letters Patent.

Patented Nov. 6, 1917.

Application filed April 30, 1917. Serial No. 165,347.

To all whom it may concern:

Be it known that I, JOHN BEISWANGER, a citizen of the United States of America, residing in the city of Steubenville, county of 5 Jefferson, State of Ohio, have invented certain new and useful Improvements in Shade-Holders, of which the following is a specification.

The modern system of illumination involves the extensive use of suspended shade bowls and reflectors of considerable size and weight. These have been supported by various means as frames, tripods and the like some of which are expensive and all of 10 which are more or less inconvenient to use. Further, their use, particularly those which clamp the shade and those the use of which involves the drilling of holes in the glass have the disadvantage that frequent break- 15 age results.

The present invention relates to a support shown in the form of a three-arm suspension or tripod which is cheap, convenient and almost automatic in its operation and 20 can be used without involving any danger of breaking the reflector shade bowl or acorn with which it may be used. It is applicable to the type having an inwardly turned flange at the upper edge which is preferably integral with the shade but may be otherwise arranged. In this support, the tension members, wires or arms of the tripod which may be three or more in number, are arranged so 25 that seen in plan they appear to be radial and their outer ends hook under the inwardly turned flange on the shade, the radius of the ends of the arms or fingers being greater than that of the inner edge of the flange. Part of the tension members 30 are made rigid and the remainder have the end portion which is hooked under the shade flange hinged so that it may be swung upward reducing the radius. The hinged joint is of the jack-knife type so that when the 35 hinged member or finger is pulled down it becomes rigid when in or near the horizontal position. While there may be any number of such arms, part made rigid and the remainder with a hinged end, in the present 40 instance I use three arms, two rigid and one

provided with the hinged end or finger. To apply to the shade, the two rigid ends or fingers are hooked under the flange and the shade is swung upward bringing the portion of the flange beneath the hinged finger 55 upward against the finger swinging it upward and inward so that the flange passes it. Then the flange is caught over the end of the finger and the shade moved down to horizontal or level position when the finger 60 is straightened out in the horizontal or rigid position, and by thus increasing the radius of the tripod, the shade is locked in position with the flange bearing on the ends of the tripod arms. 65

In the accompanying drawing I have illustrated a lighting fixture and shade bowl in connection with which is shown a three-arm support or tripod constructed in accordance with my invention. 70

In the drawing, Figure 1 is an elevation; and

Fig. 2 is a plan of the shade bowl and support, etc.

Fig. 3 shows the detail structure of the 75 jointed supporting arm.

Referring to the drawing by numerals, I have illustrated the usual lamp socket 1 shown in Fig. 1 as provided with an upper shade holder 2 and an upper shade 3. To 80 the lower portion of the outer shell of the socket I have secured the upper ends of three pendant supporting wires or arms 4, 4' and 4''. In the form of the invention shown, the upper ends of these 85 arms are placed inside the outer shell 5 of the socket and riveted thereto but they may be soldered or formed integral or otherwise secured within the scope of my invention. Each of these supporting wires or arms 4 90 extends downward from the upper end with an outward swing or curve which in the form of the invention shown becomes sharper near the bottom bringing the lower ends or fingers 6 into horizontal or near horizontal position. The exact form of 95 these arms or supporting wires may of course be widely varied within the scope of my invention, the object being to provide a plurality of hooks, arms or fingers which 100

as seen in plan extend outward radially and which are adapted to engage the inwardly turned flange 7 of a shade bowl from beneath so as to support the bowl, the radius 5 taken from the center of the fixture to the outer ends of the arms or fingers thereon being sufficient to prevent displacement, *i. e.*, greater than the radius of the inner edge of the flange 7.

10 The important feature of the present invention consists in the provision at the end of one of the supporting wires or arms, or in case there are more than three, of one or more of said arms, of a hinged finger in 15 place of the usual rigid hook or finger, the hinge being of the variety which may be termed the knife-blade type which permits the finger to bend upward but holds it rigidly in horizontal position when downward 20 force is applied to the end of the finger, such force being ordinarily due to the weight of the shade bowl suspended thereon, the finger being automatic in its action as hereinafter described.

25 The construction of the joint indicated by reference character 8, the pivoted member being indicated by reference character 9, is illustrated most clearly in Fig. 2. As shown, the inner or butt end of the pivoted member 30 is reduced forming an outwardly and downwardly inclined shoulder 10 and the end of the reduced portion at 11 is inclined in the opposite direction, *i. e.*, downwardly and inwardly. The end of the stationary 35 portion of the wire or finger 4 is correspondingly shouldered and provided with corresponding, preferably inclined contacting surfaces 12 and 13. The pivot 14 passes through the two reduced portions 15 and 40 16 near their centers. It will thus be apparent that by pushing the pivoted member 9 upward the surfaces 10 and 12 and 11 and 13 are thrown out of contact and the pivoted member swings freely, and when it is 45 brought to the horizontal position, the surface 11 is brought into contact with the surface of the stationary member at 13 and the surface 10 is brought into contact with the surface 12 of the stationary member and 50 the motion is arrested with the pivoted member in or near horizontal position. It is also apparent that when the finger is swung up, the radius at its end from the axis of the fixture is reduced and when down it is increased.

55 In operation, the flange of the shade bowl 7 is first hooked over the lower ends 6, 6 of the two stationary fingers 17 and 18. Then the flange is pressed from beneath 60 against the pivoted member 9 of the other finger C causing it to swing up.

In this way the radius swung to the ends of the fingers is reduced and the flange 7 passes up by the pivoted member; the shade

bowl is then moved slightly to one side causing it to engage the pivoted member from above and is then drawn down swinging the pivoted member to a horizontal position when the radius of the lower fingers is increased becoming greater than the radius of 65 the inner edge of the flange 7 so that the shade bowl is locked in position and can only be removed by swinging the member 9 upward as before. This may be accomplished by pushing the shade bowl up when 70 contact of the bowl with the end of the finger will swing the pivoted member into the vertical position as shown in Fig. 1 when the radius at the ends of the fingers is so reduced that the shade bowl may be removed, the inner edge of the flange passing 75 the ends of the fingers.

The added convenience of such a device over the various supports known to the art must be recognized. It is merely necessary 80 to hook the shade bowl over the two rigid fingers, push it up by the pivoted end and then draw it down when it immediately becomes locked, whereas in the majority at 85 least of the other devices it is necessary for the operator to climb to the level of the fixture whatever that is and usually manipulate the mechanism from both ends while the one described can be easily operated 90 without touching it, merely manipulating 95 and supporting the shade bowl as described.

I have thus described my invention specifically and in detail in order that its nature and operation may be fully understood; however, the specific terms herein are used 100 descriptively rather than in their limiting sense and the scope of the invention is defined in the claims.

I claim—

1. In combination in a lighting fixture, a 105 depending shade with an inwardly disposed flange, fingers extending radially of the fixture as seen in plan, the fingers extending under the flange on the shade, one of the fingers being pivoted and adapted to be bent upward from horizontal position, but rigid in horizontal position when downward force is applied.

2. In combination in a lighting fixture, a 110 depending shade with an inwardly disposed flange, fingers extending radially of the fixture as seen in plan, the fingers extending under the flange on the shade, one of the fingers being pivoted with a knife blade joint and adapted to be bent upward from 115 horizontal position but rigid in horizontal position when downward force is applied.

3. In combination in a lighting fixture, a 120 depending shade with an inwardly disposed flange, supporting arms with fingers extending outward substantially radially of the fixture as seen in plan, the fingers extending under the flange on the shade, one of the 125

fingers being pivoted with a knife blade joint so that the radius at the ends of the fingers may be reduced to permit the shade to be hooked over the fingers by hooking it 5 over the rigid fingers, pushing it upward from beneath against the pivoted finger, and then letting it rest on top of all the fingers, the pivoted finger being in this way

drawn down to a horizontal position where it is locked.

Signed by me at Steubenville, Ohio, April, 10 25th 1917.

JOHN BEISWANGER.
